[57] CLAIM

The ornamental design for a handle, as shown and described.

DESCRIPTION

FIG. 1 is a left side/top/front isometric view of a handle showing our new design, with the handle in upright position, it being understood that the carrying case shown in broken lines is for illustrative purposes only and forms no part of the claimed design;

FIG. 2 is a left side/top/front isometric view thereof, with the handle in folded position;

FIG. 3 is an enlarged front elevational view thereof;

FIG. 4 is an enlarged rear elevational view thereof;

FIG. 5 is an enlarged top plan view thereof;

FIG. 6 is an enlarged bottom plan view thereof;

FIG. 7 is an enlarged left side elevational view thereof;

FIG. 8 is an enlarged right side elevational view thereof; and,

FIG. 9 is an enlarged left side elevational view, in cross-section, taken along line “9—9” of FIG. 3, of FIG. 1.
